CLAIM

The ornamental design for a rear engine cover, as shown and described.

DESCRIPTION

FIG. 1 is a rear top perspective view of a grille showing our new design;

FIG. 2 is a rear elevation view thereof;

FIG. 3 is left elevation view thereof; and,

FIG. 4 is right elevation view thereof.

The grille is adjacent to the body of the track-type loader and thus, the bottom and front views of the grille are not visible during ordinary use and form no part of the claimed design.
